JOSEPH E. CARVER, OF BRIDGEWATER, MASSACHUSETTS.

Letters Patent No. 64,629, dated May 14, 1867.

COTTON-PICKER.

The Schedule referred to in these Letters Patent and making part of the same.

TO ALL WHOM IT MAY CONCERN:

Be it known that I, J. E. CARVER, of Bridgewater, in the county of Plymouth, and State of Massachusetts, have invented a new and improved Cotton-Picker; and that the following description, taken in connection with the accompanying drawings, hereinafter referred to, forms a full and exact specification of the same, wherein I have set forth the nature and principles of my said improvements, by which my invention may be distinguished from all others of a similar class, together with such parts as I claim, and desire to have secured to me by Letters Patent.

This invention relates to a new and improved cotton-picker designed to supersede the direct manual process, or the detaching of the cotton from the bolls directly by hand. The invention consists in the employment or use of a reciprocating tongue provided with teeth and fitted within an oblong quadrilateral box. This tongue is armed with reflex spines or teeth, and directly above it, within the box, there is an elastic plate, also armed with reflex spines or teeth, which serve to hold the cotton abstracted from the bolls and drawn into the box by the inward movement of the tongue, and insure its discharge from the rear end of the box. In the accompanying sheet of drawings—

Figure 1 is a bottom view or inverted plan of my invention.

Figure 2, a vertical longitudinal central section of the same.

Similar letters of reference indicate like parts.

A represents an oblong quadrilateral box in which a slide, B, is placed and allowed to slide freely in and out of the same. This slide rests on the bottom of the box, and is attached at its inner end to a plate, C, which is allowed to slide or work freely on the bottom of the box A, and has a pendent handle, D, attached, which extends down through a longitudinal oblong slot, a, in the bottom of the box, the length of said slot determining the length of the stroke of the slide B. This slide B should be constructed of some flexible material which will not injure or bruise the stalks of the cotton plant; vulcanized rubber, leather, or other similar material would answer. This slide (which I term a tongue) should be pointed at its outer end. (see fig. 1,) and its upper surface is armed with reflex spines or teeth b extending its whole length. In the upper part of the box A there is secured a plate, E, which may be of sheet metal or other suitable material doubled at its front end to form a spring, c, (see fig. 2,) and having its under surface provided with reflex spines or teeth d. The toothed portion of this plate extends the whole length of the box A, as shown clearly in fig. 2. The plate E is equal in width to the internal width of the box A. The implement is carried in the hand, and the slide or tongue B is shoved in and out, or has a reciprocating movement imparted to it by operating the handle D, the tongue being placed in contact with the cotton in the open bolls and drawing it out therefrom into the box A, where it is held by the teeth of the plate E, the latter preventing the cotton from being shoved out of the box by the outward movement of the tongue, but allowing the cotton in the box to be shoved backward in the box and to be discharged from the rear end of the same by the accessions the box receives at its front end by the drawing inward of the tongue. The spring or elasticity of plate E prevents the choking or clogging of the cotton within the box A. I would remark that a plurality of tongues may be used within the box, and the invention adapted for operation on a large scale.

Having thus described my invention, I claim as new, and desire to secure by Letters Patent—

The reciprocating tongue B, one or more, placed within a box, A, and armed with reflex spines or teeth, and used either with or without the toothed plate E, substantially as and for the purpose set forth.

The above specification of my invention signed by me this 26th day of March, 1867.

JOSEPH E. CARVER.
